UNITED STATES PATENT OFFICE.

MAXIMILIAN C. FRINS, OF NEW YORK, N. Y., ASSIGNOR TO INTERNATIONAL MOTOR COMPANY, OF NEW YORK, N. Y., A CORPORATION OF DELAWARE.

SHIFTER-FORK PLUNGER.

1,378,222.

Specification of Letters Patent. Patented May 17, 1921.

Application filed August 26, 1920. Serial No. 406,157.

To all whom it may concern:

Be it known that I, MAXIMILIAN C. FRINS, a citizen of the United States, residing in the borough of Manhattan of the city of New York, in the State of New York, have invented certain new and useful Improvements in Shifter-Fork Plungers, of which the following is a specification, reference being had to the accompanying drawing, forming a part hereof.

This invention relates to an improved plunger for positioning shifter forks and also to an improved association thereof with a positioning groove for the fork cut transversely in the supporting shaft on which the fork slides. Heretofore, plungers for the purpose noted have usually been formed with a generally conical end adapted to seat in a similar recess in the shaft or in a transverse groove cut in the shaft. The bearing end for the plunger has heretofore usually afforded a one-point support with the result that upon shifting of the fork the nose of the plunger would nick the groove at its edge and ultimately ream a longitudinal channel in the shaft along the path of movement of the plunger. This nicking has resulted in a breaking down of the holding wall of the groove to such an extent that the fork is often accidentally shaken from its position when the plunger rides loosely out of the nicked groove. Further, the shaft itself is marred and little resistance offered to the free sliding of the fork. By the improved construction it is sought to provide a plunger which is of such character as to prevent the positioning groove from being nicked or worn to any appreciable extent and to rest on the shaft with a relatively broad bearing surface so as to wear it uniformly, if at all, and not mar its exterior surface. In accordance with the invention the nose of the plunger is formed by tapering it at opposite sides leaving a transverse blunt nose which is milled out concentrically with the shaft so as to form a broad and long bearing surface conforming to the curvature of the shaft. The entering groove for the plunger is similarly formed with tapered side walls and a relatively wide bottom, the result being that when the plunger is forced out of the notch it rides out with a line contact between it and the edge of the notch.

In the preferred form of the invention the plunger is held against rotative movement within the hub of the fork by means of a positioning pin which has a slotted engagement with the plunger.

Reference is now to be had to the accompanying drawing for a detailed description of one embodiment of the invention, in which—

Figure 1 is a view in elevation of a shifter fork of approved type and in section through the hub thereof and the improved positioning plunger, the nose of the plunger being indicated in elevation.

Fig. 2 is a view in transverse section taken through the hub of the fork shown in Fig. 1 along the plane of the line 2—2 and looking in the direction of the arrows, the shaft and plunger being shown in plan.

The fork *a* which may be of any approved form may be cast as usual with an elongated hub *a'* through which passes a supporting shaft *b* along which the fork is slid in a manner which will be understood. The position of the fork with its gear is, of course, determined by the position in which it is arrested in its movement along the shaft *b*. For the purpose of fixing this position and indicating to the operator when a desired position is reached, it is usual to mount with the hub *a'* a positioning plunger indicated at *c* and adapted to cooperate with notches or the like, indicated at *b'*. The plungers heretofore employed have been objectionable in that their noses have usually been formed to afford such a bearing as would nick the positioning recess or notch in the shaft and would, indeed, have a tendency to cut a groove along the shaft in the path of travel of the plunger with the fork. The present invention seeks to provide an improved plunger which is of such form as to eliminate any reaming action by its nose on any metal with which it engages. Accordingly, the plunger *c* at its inner end is tapered at opposite sides, as indicated at *c'*, *c''* terminating in a blunt nose, indicated at *c³*. The nose *c³* is milled out transversely, as indicated at *c⁴* along a line substantially concentric in curvature with the curvature of the supporting shaft *b*. The entering groove or notch *b'* for the plunger *c* is cut of generally similar form to the end of the plunger

c as described in that this notch has opposed side walls *b*² and a broad bottom *b*³, the form and dimensions being such as to receive snugly the tapered nose of the plunger. 5 The plunger *c* may be hollow for a portion of its length to receive a spring *d* which may seat on a plate *e* held against movements by a cotter pin *f* which may pass through the extension *a*² of the hub *a*' in which the 10 plunger is positioned. The cotter pin *f* rests in opposed slots *c*⁵ cut in the side walls of the plunger adjacent its end so as to permit axial movement of the plunger.

In operation it will be evident that the 15 plunger *c* is pressed yieldingly into engagement with the shaft *b* at all times under the influence of the spring *d*. When the fork *a* is slid along the shaft by any usual means the plunger *c*, of course, rides out of the 20 notch *b*' with which its nose engages, moving axially against the pressure of the spring *d*. In riding out of the notch *b*' it is evident that one of the tapered side walls *c*', *c*² of the nose of the plunger *c* will remain in 25 engagement with one of the tapered side walls *b*² of the notch until the end of the plunger passes out of the notch when the edge of the curved end *c*⁴ of the plunger will have a moment to engage the edge of one of the 30 side walls *b*². At that instant there will be a line of contact of substantial length between the two edges. This kind of contact will prevent any nicking or undue wear on the metal of the shaft. When the plunger 35 finally rides on to the exterior surface of the shaft *b* the curved end *c*⁴ will rest snugly on the shaft and afford a relatively broad and long bearing surface for the plunger. The wear occasioned by the plunger on the 40 shaft will be negligible and, of course, uniform. There will be no tendency for the plunger to groove or nick the shaft at any point. The engagement of the cotter pin with the slot *c*⁵ in the plunger will maintain 45 it at all times in proper relation to the transverse notches *b*', although in some construc-

tions it may be found unnecessary to provide any such positioning devices.

I claim as my invention:

1. As an article of manufacture, a shifter 50 fork plunger having a nose formed with oppositely tapered side walls terminating in a blunt nose curved transversely.

2. As an article of manufacture, a shifter 55 fork plunger formed at one end with oppositely tapered walls terminating in a blunt nose curved concentric to the shaft with which the plunger coöperates.

3. As an article of manufacture, a shifter 60 fork plunger recessed at one end to receive a spring and slotted adjacent said end to receive a positioning pin to hold the plunger in predetermined axial position and formed at its other end with a blunt nose curved transversely and concentrically with the 65 shaft with which the plunger coöperates.

4. In combination with a shifter fork and a supporting shaft on which the fork is slidably mounted, a plunger carried with the fork and having one end formed with oppositely tapered slots terminating in a flat blunt 70 nose curved transversely, said shaft being provided with coöperating grooves cut transversely to the axis of the shaft and formed similarly to the nose of the plunger. 75

5. In combination with a shifter fork and a supporting shaft on which the fork is slidably mounted, a plunger carried with the fork and having one end formed with oppositely tapered slots terminating in a flat 80 blunt nose curved transversely along a line concentric to the shaft, said shaft being provided with coöperating grooves cut transversely to the axis of the shaft and formed with opposed side walls tapered similarly 85 to the tapered nose of the plunger and with a broad flat bottom to receive the flat nose of the plunger.

This specification signed this 20th day of August, A. D. 1920.

MAXIMILIAN C. FRINS.
